VALVE BOX

Albert Herbert Goyen, 17 Marie Dodd Crescent,
Blakehurst, New South Wales, Australia

Filed Dec. 27, 1972, Ser. No. 318,732

Claims priority, application Australia June 30, 1972

Term of patent 14 years

Int. Cl. D23—01

U.S. Cl. D23—19

FIG. 1 is a top isometric view of a valve box showing my new design;

FIG. 2 is a bottom isometric view thereof;

FIG. 3 is a cross-sectional view taken on line 3—3 of FIG. 1; and

FIG. 4 is a cross-sectional view taken on line 4—4 of FIG. 2.

I claim:

The ornamental design for a valve box, as shown.
